METHOD AND APPARATUS FOR SUSPENDING PIPE IN BOREHOLES

Mercer H. Parks and Marvin R. Jones, Houston, Tex., assignors, by mesne assignments, to Standard Oil Development Company, Elizabeth, N. J., a corporation of Delaware

Application December 3, 1948, Serial No. 63,406

13 Claims. (Cl. 166—1)

1

This invention relates to new and useful improvements in methods and apparatus for suspending and supporting tubular conductors, such as pipe, within a borehole.

The invention relates particularly to a method and means for suspending well casing or the like in well bores which initially penetrate or traverse an incompetent strata or formation having insufficient mechanical strength to support the weight of the pipe in the borehole.

In the drilling of wells for oil, gas and other fluids, it is the general practice to employ casing or pipe to line the walls of the borehole for protection against caving formations, salt water entry, or for other reasons, and well casings of gradually diminishing diameters are run in as the drilling of the borehole proceeds and each string of casing has the lower end cemented in place. The outer or largest diameter casing, usually referred to as the surface casing, is set first and extends only a relatively short distance, possibly 300 to 400 feet below the derrick floor and is firmly anchored to the sub-surface formation, said casing being usually cemented to the sub-surface formation throughout its entire contact with said formation.

A casing head is mounted on the upper end of the surface casing above the ground level and the first inner string of casing is run therethrough with its lower end extending a considerable distance below the outer casing, this lower end being cemented in place. Through the usual hanger arrangement within the outer casing head, the inner casing string is suspended, whereby the weight of the inner casing is transferred through the casing head to the outer casing and then through said outer casing to the sub-surface formation within which said outer casing is anchored. The required number of inner casing strings, which vary according to the depth of the particular well, as well as the well tubing through which the well fluids are ultimately produced upon completion of the well, are progressively run in and suspended by the usual casing and tubing head arrangements. Each inner string has its weight transferred through the casing or tubing head arrangement to the outer surface casing and through said casing to the sub-surface formation within which the outer casing is anchored. The point of suspension or support for the various inner strings is at the surface usually just below the derrick floor.

So long as the sub-surface formation extending downwardly from the earth's surface and

5 within which the outer casing is firmly anchored, is of sufficient strength to give the casing adequate lateral support, said casing is capable of bearing the weight of the various and relatively long inner strings of pipe or casing, and suspending or supporting the upper ends of the inner strings at a point adjacent to the derrick floor at the upper end of the surface casing is satisfactory. In other words, if the formation immediately below the earth's surface is a competent one and capable of imparting sufficient lateral support to the outer surface casing, the transfer of the weight of the inner strings of pipe through the usual casing and tubing head arrangements above the earth's surface may be effectively carried out.

20 However, in the drilling of wells at sea or offshore, such as on the continental shelf in the Gulf of Mexico, off coastal Louisiana and Texas, the initial sub-surface formation at the ocean floor which is encountered is ordinarily an incompetent one and although it may provide some lateral support, it does not have sufficient strength to impart the necessary or required lateral support to the outer casing which would allow the transfer of considerable weight through the casing. It has been found that the formation at the bottom of the sea or ocean floor consists of a structure which is of insufficient strength to reinforce the outer casing and to support the weight of the inner pipe strings and this incompetent formation may extend from 50 to several hundred feet below the ocean floor. Of course, the derrick floor is above the water level so that the outer casing initially extends through the water which may have a depth of thirty to one hundred feet and this distance added to the depth of the incompetent formation at the ocean floor may locate the first competent sub-surface formation at a relatively great distance from the derrick floor. Thus, with the outer or surface casing firmly anchored in the first or initial competent formation, the upper end of said outer casing may be disposed from one hundred to several hundred feet from the point of anchorage, with the intermediate section of casing traversing the incompetent formation and the water. Besides the incompetent formation and water traversed by the section of casing, it also 30 is exposed to the air for the distance between the water level and the derrick floor which may be as much as 50 feet. No support through this distance is obtained.

25 The wave action in waters of considerable depth impose a lateral load on a vertical column

such as the outer well casing and obviously, if said outer casing is not anchored for a relatively great distance from its upper end because of its extending through the water and also because of the lack of a competent formation immediately below the ocean floor, it is unstable and does not have the desired rigidity for carrying the heavy vertical loads imposed by the multiple inner casing strings. Therefore, in marine drilling suspension of the inner strings of pipe or casing by means of the usual casing head arrangements at the upper end of the outer casing adjacent the derrick floor is not practical. The transfer of the weight of the inner strings through the relatively unstable and unreinforced upper portion of the outer casing, which casing is constantly subjected to the wave action, is obviously most undesirable, since there is a constant risk of straining said outer casing beyond the breaking point. Also, suspension of the inner casing strings from the unstable upper end of the outer casing results in an instability of the upper portions of the inner strings with the result that the danger of shearing or breaking of all of the casing strings is constantly present.

The same difficulty with respect to supporting or suspending the inner strings of pipe or casing may also be encountered in some types of marshy or swampy terrain where the upper level or initial formation of the earth consists of sedimentaceous, unconsolidated deposits of insufficient strength to give the outer casing the required lateral support. As a matter of fact, the problem exists in any area or terrain where the initial sub-surface formation is incompetent and has insufficient strength to reinforce the outer casing and to support the weight of the pipe strings, with the result that the outer casing cannot be anchored except at a point considerably below the earth's surface which is, of course, at a point some distance from the upper end of said casing.

It is, therefore, one object of the present invention to provide an improved method and apparatus for efficiently suspending or supporting pipe, such as well casing, within a borehole which initially penetrates or traverses an incompetent formation and then extends into and through a competent formation.

An important object of the invention is to provide an improved method for suspending pipe within a well bore which initially penetrates an incompetent zone or formation and then extends through a competent formation, said method including, running an outer casing within the borehole so that said casing completely traverses the incompetent zone or formation and extends into the competent formation; anchoring the outer casing within the competent formation, running an inner pipe string within the outer casing whereby said inner string extends entirely therethrough, and supporting the inner pipe string within the outer casing at a point at which the casing has adequate strength to effectively support the weight of the inner string so that the weight of said inner pipe string is directly transferred through the outer casing to the competent formation within which said outer casing is anchored.

Another object of the invention is to provide an improved method, of the character described, whereby a plurality of inner pipe strings may be effectively mounted or suspended, one within the other, and all within an outer casing, which casing is anchored within a competent subsur-

face formation located beneath an incompetent zone or formation in a well bore; all of said inner pipe strings being suspended or supported at a predetermined point within the outer casing so that the weight of said pipe strings is effectively transferred through the outer casing and thence to the competent formation within which the outer casing is anchored.

A further object of the invention is to provide an improved pipe suspending apparatus which permits an inner pipe string to be suspended or supported within an outer pipe string at any desired point within the outer string, whereby the particular location of the point of suspension or support of the inner string may be selected or predetermined to position said support adjacent a competent sub-surface formation capable of carrying the weight or load which is transferred through the support and outer pipe string to said formation.

A particular object of the invention is to provide an improved pipe-suspending or supporting apparatus which is constructed to operate within the annular space between the inner and outer pipe strings and which is adapted to be actuated without the necessity of rotating or otherwise manipulating the inner pipe string, whereby said inner pipe string may have its lower end cemented in the sub-surface formation before the pipe-suspending apparatus is operated to transfer the weight of said inner string to an outer pipe string and to the competent sub-surface formation within which said outer string is anchored; said apparatus being constructed so that it may be set in the annular space between adjacent pipe strings without sealing said annular space, whereby release of pressure or passage of fluids through the annular spaces to and from the surface may be accomplished after the apparatus is in its set position.

A still further object of the invention is to provide an improved pipe-suspending method and means which is particularly adapted for marine drilling, wherein the outer or surface casing is anchored within a competent formation within a borehole which formation is located a relatively great distance from the upper end of said outer casing, with the result that the upper end portion of said casing is unstable and lacks desired rigidity; the improved method and means contemplating the suspension of the inner pipe strings within the outer casing at a point or elevation in the general vicinity of the point of anchorage of said outer string, whereby the point of support of said inner strings is well below the upper end of said strings and below the unstable upper portion of said outer casing to assure effective transfer of the weight of the inner pipe strings to the competent formation within which the outer casing is anchored, packing off between the various inner pipe strings and also between the inner string adjacent the outer casing and said casing being accomplished adjacent to or relatively close to the upper ends of the pipe strings and casing, preferably at substantially the derrick floor level.

Other and further objects and advantages will be understood by those skilled in this art from a consideration of the subsequent description or will be apparent or pointed out hereinafter.

In the accompanying drawings wherein I have illustrated a preferred embodiment of the present invention and wherein like numerals designate corresponding parts throughout the various views:

Fig. 1 is a schematic, sectional view of a typical well bore drilled at sea or offshore and illustrating the various pipe strings supported by gripping slips;

Fig. 2 is a diagrammatic view illustrating the manner of transferring the weight of each inner pipe string outwardly to the outer casing;

Fig. 3 is an enlarged, sectional view illustrating a modified form of apparatus for supporting the pipe strings; and,

Fig. 4 is a sectional view illustrating another means for supporting the inner pipe string.

As used herein, "earth's surface" is meant the surface of the earth as envisioned by cartographers. Some places on the earth's surface may be below sea level and where the earth is penetrated by the drilling bit is considered to be the earth's surface in the present invention. In marine drilling, the earth's surface will be the level of the sea and not the ocean floor. In marshy or swampy terrain, the earth's surface will be the surface exposed to the atmosphere, whether it be earth or water. Also, as referred to herein, "incompetent zone or formation" is meant to include any zone or area, such as water, or any formation which has insufficient strength to give the casing extending therethrough the required lateral support.

The present invention will be described as used in marine drilling, wherein a well is drilled offshore or at sea, such as along the continental shelf in the Gulf of Mexico. In the drilling of such wells, it is customary to erect a platform or derrick floor 10 at a sufficient distance above the sea level to allow for safe working conditions. The platform is usually supported by pilings 11 which are driven into the ocean floor a sufficient distance to support the weight of the derrick and its auxiliary equipment. The borehole is then drilled in the usual manner down through the ocean floor and into the formations which it is desired to penetrate. As illustrated in Fig. 1, the borehole 12 first penetrates an incompetent structure or sub-surface formation A and then traverses a competent structure B. Of course, the zone or area between the water level and the ocean floor is also to be considered an incompetent zone or formation, since obviously, the water is not capable of imparting lateral support to the well casing.

As is well known, it is customary practice to case the borehole 12 with a series of casing or pipe strings of varying diameters and a typical arrangement is illustrated in Fig. 1. As shown, the outer or so-called "surface casing" 13 is run in and cemented as indicated at 14 after the well bore has been drilled to a depth penetrating the initial competent structure B. The cement 14 firmly anchors the outer or surface casing 13 to the competent formation B, whereby said casing is firmly anchored in position. The length of the outer casing 13 will, of course, be variable with each well, but presuming the water which is an incompetent zone to have a depth of fifty feet with the initial incompetent structure A extending for sixty feet, it would probably be desirable that the outer casing 13 have an overall length of three hundred feet, whereby an ample portion of said casing is disposed within the competent formation B. It will be evident that by anchoring the casing 13 within the competent formation B, said casing will be rigidly connected therewith; however, because the formation B is at a considerable distance from the derrick floor 10 to which the upper end of

the casing 13 extends, it will be evident that a considerable portion of the casing 13 extends through the incompetent formation A and also through the incompetent zone formed by the water above the ocean floor. The formation A may impart some lateral support to the casing but such support will be inadequate to reinforce that portion of the casing extending therethrough sufficiently to permit said portion to carry a relatively heavy load. Thus the upper portion of the outer casing 13 which is subjected to the lateral stresses induced by the wave actions is more or less unstable and lacks rigidity as a heavily loaded column. Because the competent formation B is disposed a considerable distance below the derrick floor 10, the point of anchorage of the outer casing is at a considerable distance below the upper end of said casing.

As illustrated, the outer casing 13 is shown as anchored in the first competent formation B below the initial incompetent formation A, but it is apparent that if desired the borehole may be drilled downwardly below the formation B and the casing anchored in such lower formation. As a matter of fact, the derrick is ordinarily supported at its four corners by the piling 11, and this results in projected bulbs of weight distribution which extend some distance below the earth's surface. It is desirable and preferable that the competent formation to which the outer casing 13 is anchored be below the bulbs of weight distribution of the derrick structure. The exact distance, as has been stated, will be variable, but ordinarily formations competent to support the casing 13 may be anywhere from one hundred to six hundred feet below the water level.

After the outer or surface casing 13 has been cemented or anchored in place, the borehole drilling proceeds with the diameter of the borehole being reduced as indicated at 12a, and drilling in this manner may proceed for two or three thousand feet, at which time it is desirable to set the first inner string of casing 15. The casing 15 is of substantially the same diameter as the reduced portion 12a of the bore 12 and is obviously of less diameter than the outer casing 13. The inner string is run within the reduced portion 12a and has its lower end cemented as indicated at 16 within the lower portion of the bore. The cementing operation is carried out while the inner string 15 is supported by suitable means within the derrick, and after the cement has set, it is desirable to transfer the weight of the inner casing 15 to the outer casing 13 and then to the competent formation B.

As has been explained, it has been the practice in the past to provide a casing head at the upper end of the outer casing 13 and to suspend or support the inner casing string 15 through the usual casing head support arrangement. However, because the upper portion of the outer casing 13 is unstable as a heavily loaded column due to the fact that a relatively large portion thereof extends through the incompetent zone formed by the water and the formation A, it is not practical to locate the support at the extreme upper end of said casing. If the point of suspension for the inner casing 15 is at the upper end of said casing, it will be evident that the weight of the inner string 15 would be transferred solely through the unstable upper portion of the outer casing and then to the competent structure. The unsupported upper end of the outer casing 13 which does not have the required lateral reinforcement does not have adequate

strength to transfer this weight downwardly therethrough to the competent structure. Further, since this upper portion extends through the water, it is constantly subjected to the lateral stresses exerted by the wave actions which place an additional strain thereon.

In carrying out the present invention, the inner casing 15 is suspended or supported within the outer casing 13 at a point below the unstable upper portion of said casing. As shown in Fig. 1, suitable slips 17 are disposed between the inner casing 15 and are arranged to engage the wall of the outer casing 13. The slips are shown more or less schematically and may be of any type which may be set within the annular area between the casings and without rotation or other manipulation of the inner casing or pipe 15. The slips are disposed at any elevation at which the outer casing has sufficient lateral support to carry the load and said slips function to effectively transfer the weight of the inner string of casing 15 to the outer string 13 and then directly to the competent formation B which is capable of supporting this weight. The annular space between the inner casing 15 and outer casing 13 may be packed off by any suitable seal S which is preferably located at the upper ends of the casings near or adjacent the derrick floor 10. Obviously, the slips operate in the annulus between the casings and since the seal S is located at the upper end thereof the annular space is accessible from the surface. Also the slips do not seal or pack off the annulus so that flow of pressure fluid or release of pressure within said annulus may be carried out after said slips are in a set position.

From the foregoing, it will be evident that the inner casing string 15 is effectively supported within the outer casing with the load or weight of said inner string being transferred through the outer casing to the formation B which is capable of supporting the weight. The slips 17 are preferable since they may be selectively set at the desired elevation or location. The slips 17 are illustrated as set at an elevation substantially opposite the competent formation B but it is noted that the particular elevation at which the slips 17 are located is variable and is dependent upon the conditions encountered in the well bore. As has been explained, the incompetent structure A does not give the casing 13 the required lateral support which would permit the point of suspension of the inner string to be at the extreme upper end of the outer casing, as is the usual practice in ordinary land drilling; however, the formation A does impart some lateral support and therefore, the slips 17 may in some instances be set in the outer casing 13 at some point or elevation above the competent formation B. It will be apparent that the inherent strength of the casing, together with the relatively weak lateral support afforded by the incompetent formation A, will allow an effective transfer of the load of the inner string at some point above the competent formation B and thus, the slips 17 are set at any point in the outer casing at which said casing has sufficient stability and strength to efficiently transfer said load to the competent formation. By disposing the point of suspension of the inner casing at an elevation which effectively transfers the load through the outer casing to the competent formation, the upper unstable portion of the outer casing 13, which is that portion extending through the incompetent formation A and also through the

water, is not subjected to any load. The casing has ample inherent strength as a column to withstand the lateral stresses due to the wave action provided that said casing need not carry any additional load.

The well bore is completed by progressively reducing its diameter as indicated at 12b and 12c and additional inner strings 15a and 15b are successively run in and set within the well bore. The inner casing string 15a which is cemented at 14b in the reduced section 12b of the bore is supported by slips 17a which are similar to the slips 17. The slips 17a, which are mounted on the string 15a, engage the bore of the inner casing 15 and thus, the weight of the string 15a is transferred through the slips 17a and 17 to the outer casing and then to the competent formation B. The string 15b has its lower end cemented at 14c within the reduced section 12c of the well bore, and is illustrated as extending into the producing sand C or formation C. The string 15b is supported by slips 17b which are similar in construction to the slips 17a and 17. The slips 17a and 17b are also illustrated as located at an elevation or point opposite the competent formation B, although, as has been pointed out, these slips may be set at an elevation where the outer casing has sufficient strength to effectively transfer the load to the competent formation.

The annular space between the string 15a and the string 15, as well as the annular space between the string 15b and the string 15a, are packed off by suitable seals S which may be of the same construction as the seal employed for packing off between the outer casing 13 and the first inner string 15. These seals are preferably located at or adjacent the derrick floor 10.

From the above, it will be seen that all of the inner strings are suspended so as to be effectively supported by the competent formation B. The weight of each inner string is transferred through its slip support and the adjacent outer string to the outer casing 13 and then to the competent formation within which the outer casing is firmly anchored. The upper portions of all of the casing strings extend upwardly through the incompetent formation A and also through the water above the ocean floor. However, these upper portions which are subjected to the lateral forces exerted by the wave action do not carry any particular load and their inherent strength is capable of withstanding such stresses so long as they are not forced to carry additional load. The transfer of weight of the inner strings to the outer casing is at a point where the outer casing has adequate strength to transfer the load through the firm anchorage or cement 14 to the competent formation B which is capable of supporting such load.

After the various casing strings, which may vary in number in accordance with the particular well and its depth, have been set, the well tubing T may be run through the innermost casing 15b and may, if desired, be supported by slips 17c which are of the same construction as the slips 17, 17a and 17b. In this manner, the weight of the tubing string T will be transferred through the various inner casings to the outer casing 13 and then to the competent supporting formation B. A suitable annular seal S located at or adjacent to the derrick floor 10 may pack off the annular space around the well tubing T and the casing 15b. Production of the well may then be

upwardly through the tubing string T in the usual manner.

The particular method of supporting the various pipe strings is clearly illustrated in Fig. 2 and as shown in this figure, the first inner casing 15 is provided with coupling collars 30 and 31 which are utilized to connect the supporting slip assembly in said casing string. The lower coupling 30 is designed so as to carry the lower portion of the casing 15 therebelow in tension, while the weight of the upper portion of the casing 15 above the upper coupling 31 is carried by said collar in compression. The weight is transferred through the collar 31 and through the slip assembly 17 to the outer casing. As shown, the slips 17 are set adjacent or opposite the cemented portion of the outer casing so that a direct transfer of the load to the competent formation is effected. However, as has been pointed out, the slips 17 may be set at any level or elevation within the casing 13 where the outer casing has sufficient strength to transfer the weight of the inner strings to the competent formation. Thus, the exact location of the slips is variable within limits and is controlled by the load imposed by the inner strings, as well as by the amount of lateral support which the outer casing 13 is given by the incompetent formation.

The remaining inner strings are suspended in the same manner as the string 15, with the string 15a having couplings 30a and 31a which connect the slips 17a in said string. Couplings 30b and 31b are connected in the innermost casing string 15b and function in the same manner as the couplings 30 and 30a and the couplings 31 and 31a. The slips 17a and 17b are illustrated as set at respectively higher elevations which is possible since the load of each outer string is transferred to the next outer string and finally to the outer casing 13 and competent formation B. It is apparent that the casing 15 is anchored at the slips 17 and thus the slips 17a transferring the weight of the next inner string 15a may be set at any point within the string 15 where said string 15 has sufficient strength to transfer the load. Similarly, the innermost string 15b may have its slips set at any point above or below the anchor point of slips 17a where the string 15a has adequate strength to effectively transfer the load. It is obvious that with the arrangement shown, the weight of the inner strings is progressively transferred through the various strings to the other casing and through said outer casing to the competent formation.

The use of the slips 17 to 17c is desirable since slips may be more readily set at desired or predetermined locations. However, it is possible to carry out the present invention with an arrangement such as shown in Fig. 3, wherein the outer or surface casing 13 which is anchored within the competent formation B is provided with a special coupling collar 20 having an internal flared seat 21. The inner casing 15 also has a special coupling collar 20a connected therein and the outer surface of this collar is adapted to engage the seat 21 to thereby support the inner casing within the outer casing 13 and to transfer the weight of said inner casing to the competent formation B. Suitable by-pass openings 22 may be formed in the coupling 20a to permit by-pass of fluid as the inner casing is lowered. Similarly, the next inner casing 15a is provided with a special coupling 20b which has its outer surface adapted to engage a seat 21a formed within the coupling 20a of the casing 15. Ob-

viously, the weight of the innermost casing 15a will be transferred through the couplings 20b and 20a to the outer casing 13 and thence to the competent formation B. Obviously, the supporting 5 couplings will function in exactly the same manner as the slips 17.

Still another method of supporting the inner casing with respect to the outer casing is illustrated in Fig. 4. In this case, only the outer casing 13 and the first inner casing 15 is illustrated. After the inner casing is in position, a suitable cement plug 23 may be formed by introducing the cement slurry perforations 24 in the inner casing where it is allowed to set so as to form an annular connection between the inner casing 15 and the outer casing 13. As an alternative procedure, the plug may be formed by pumping the required quantity of cement down the annulus between 13 and 15 followed by the necessary amount of mud to place the cement at the desired support position which is located at a point where the outer casing has sufficient strength to transfer the load to the competent formation B. It will be apparent that this arrangement will transfer the weight of the inner string to the outer casing and then to the competent formation B. In the form shown in Fig. 3, it is necessary because of the special couplings having the inclined seats therein to reduce the size of the casing strings at the point of connection of said coupling. This is a somewhat undesirable feature since different size pipe must be employed in the same string; however, so far as the support or suspension of the inner strings is concerned, the forms illustrated in Figs. 3 and 4 will function efficiently to transfer the weight of said strings to the competent formation which is, as explained, at some distance below the upper end of the various pipe strings and below the derrick floor.

Although the invention has been shown and described as employed in marine drilling, it is evident that it may be effectively used in any area where the initial zone or formation penetrated by the borehole is of an incompetent nature. It will be apparent that the improved method contemplates the transfer of the weight of the inner pipe strings through each other and to the outer casing at a point where the load may be effectively transferred to the first competent formation, rather than through a casing and tubing head assembly at the extreme upper end of the various pipe strings as has been the practice in the past. It will be evident that any number of inner casing strings may be employed depending upon the particular well and its depth.

The foregoing description of the invention is explanatory thereof and various changes in the size, shape, and materials, as well as the details of the illustrated construction, may be made within the scope of the appended claims without departing from the spirit of the invention.

Having described the invention, we claim:

1. The method of suspending an inner pipe string having its upper end at least above the earth's surface within a well bore which initially traverses a zone of a strength incompetent to bear the weight of said inner pipe string and which then extends through a competent subsurface formation, said method including, lowering a well casing within the upper portion of the bore to locate the lower end of said casing within the competent sub-surface formation with the upper portion of said casing traversing the incompetent zone, anchoring said casing to said

11

competent formation, lowering an inner pipe string within the casing, suspending said inner pipe string intermediate its upper and lower end thereof from the casing at a point within the outer casing where said casing is of sufficient strength to effectively transfer the weight of said inner string to the competent formation within which the outer casing is anchored, and maintaining said suspended inner pipe string in said casing with its upper end extending at least above the earth's surface and with its lower end extending downwardly to a point below the lower end of said casing.

2. The method of suspending an inner pipe string having its upper end at least above the earth's surface within a well bore which initially traverses a zone of a strength incompetent to bear the weight of said inner pipe string and which then extends through a competent sub-surface formation, said method including, lowering a well casing within the upper portion of the bore to locate the lower end of said casing within the competent sub-surface formation with the upper portion of said casing traversing the incompetent zone, anchoring said casing to said competent formation, lowering the inner pipe string within the casing, suspending said inner pipe string intermediate its upper and a lower end thereof from the casing at a point within the outer casing where said casing is of sufficient strength to effectively transfer the weight of said inner string to the competent formation within which the outer casing is anchored, and sealing the annular space between the inner pipe string and the outer casing at the upper ends of said casing and string and at a point above the incompetent zone.

3. The method of suspending an inner pipe string having its upper end at least above the earth's surface within a well bore which initially traverses a zone of a strength incompetent to provide appreciable lateral support to a vertical column and which then extends through a competent sub-surface formation, said method including, lowering a well casing within the upper portion of the bore to locate the lower end of said casing within the competent sub-surface formation with the upper portion of said casing traversing the incompetent zone, anchoring said casing to said competent formation, lowering the inner pipe string within the casing, connecting the inner pipe string at a point intermediate its upper and a lower end thereof to the casing at an elevation below the incompetent area traversed by the casing and at a point substantially adjacent the competent formation, whereby the weight of said inner pipe string is transferred to the casing and to the competent formation in which said casing is anchored, and maintaining said connected inner pipe string in said casing with its upper end extending at least above the earth's surface and with its lower end extending downwardly to a point below the lower end of said casing.

4. The method of suspending an inner pipe string having its upper end at least above the earth's surface within a well bore which initially traverses a zone of a strength incompetent to provide appreciable support to a vertical column and which then extends through a competent sub-surface formation, said method including lowering a well casing within the upper portion of the bore to locate the lower end of said casing within the competent sub-surface formation with the upper portion of said casing traversing

12

the incompetent zone, anchoring said casing to said competent formation, lowering the inner pipe string within the casing, supporting the inner pipe string intermediate its upper and a lower end thereof within the casing at a predetermined point within said casing which is at a point where the load may be effectively transferred through the casing to the competent formation in which said casing is anchored, maintaining said supported inner pipe string in said casing with its upper end extending at least above the earth's surface and with its lower end extending downwardly to a point below the lower end of said casing and sealing the annular space between the inner string and the casing.

5. The method as set forth in claim 3, with the additional step of sealing the annular space between the inner pipe string and the casing.

6. For use in a well bore which initially penetrates and traverses an incompetent zone which is incapable of forming a support for a well casing and which then penetrates a competent formation, a well casing extending within and through the bore to completely traverse the incompetent zone and having its lower end extending into the competent formation, means for anchoring said well casing to said competent formation, an inner pipe string extending with its upper end at least above the earth's surface longitudinally within the bore of the casing, and means for transferring the weight of said inner string intermediate its upper and a lower end thereof to the casing at a point where said casing has adequate strength to effectively transfer said weight to the competent formation, said inner pipe string extending upwardly in said casing from the point where its weight is transferred to the casing so that the upper end of the inner pipe string is at least above the earth's surface and downwardly from the weight transferring point to a point below the lower end of said casing.

7. For use in a well bore which initially penetrates and traverses an incompetent zone which is incapable of forming a support for a well casing and which then penetrates a competent formation, a well casing extending within and through the bore to completely traverse the incompetent formation and having its lower end extending into the competent formation, an inner pipe string extending with its upper end at least above the earth's surface longitudinally within the bore of the casing, means for transferring the weight of said inner string intermediate its upper end and a lower end thereof to the casing at a point below the incompetent formation and substantially opposite the competent formation, said inner pipe string extending upwardly in said casing from the point where its weight is transferred so that the upper end of the inner pipe string is at least above the earth's surface and downwardly from the weight transferring point to a point below the lower end of said casing and means for sealing the annular space between the inner pipe string and the casing.

8. The combination as set forth in claim 6, wherein the means for transferring the weight of the inner string to the outer string comprises gripping slips carried by the inner string and having gripping means engageable with the bore of the casing.

9. The combination as set forth in claim 6, wherein the means for transferring the weight of the inner string to the outer string comprises

a coacting seat and shoulder on said string and casing.

10. The combination as set forth in claim 6, wherein the means for transferring the weight of the inner string to the outer casing is an annular cement plug.

11. For use in a well bore which initially penetrates and traverses an incompetent zone which is incapable of forming a support for a well casing and which then penetrates a competent formation, a well casing extending within and through the bore to traverse completely the incompetent formation and having its lower end extending into the competent formation, an inner pipe string extending with its upper end at least above the earth's surface longitudinally within the bore of the casing, means for transferring the weight of said inner pipe string intermediate its upper end and lower end thereof to the casing at a point below the incompetent formation and substantially opposite the competent formation, and means for sealing the annular space between the inner pipe string and the casing arranged adjacent the upper ends of the inner pipe string and the casing.

12. For use in a well bore which initially penetrates and traverses an incompetent zone which is incapable of forming a support for a well casing and which then penetrates a competent formation, a well casing extending within and through the bore to traverse completely the incompetent zone and having its lower end extending into the competent formation, means for anchoring said well casing to said competent formation, a first inner pipe string extending with its upper end at least above the earth's surface longitudinally within the bore of the casing, means for transferring the weight of the first inner string intermediate the upper and lower ends thereof to the casing at a point where 40 said casing has adequate strength to transfer said weight to the competent formation, a second inner pipe string extending through the first inner pipe string, and means for transferring the weight of the second inner string to the first 45 inner string and through said first inner string to the well casing and competent formation.

13. The method of suspending an inner pipe

string having its upper end at least above the earth's surface within a well bore which initially traverses a zone of a strength incompetent to provide appreciable lateral support to a vertical column and which then extends through a competent sub-surface formation, said method including lowering a well casing within the upper portion of the bore to locate the lower end of said casing within the competent sub-surface formation with the upper portion of the said casing traversing the incompetent zone, anchoring said casing to said competent formation, lowering the inner pipe string within the casing, connecting the inner pipe string intermediate its upper and lower ends thereof to the casing at an elevation below the incompetent area traversed by the casing and at a point substantially adjacent the competent formation whereby the weight of said inner pipe string is transferred to the casing and to the competent formation in which said casing is anchored, sealing an annular space between the inner string and the casing at a point adjacent the upper ends of the inner pipe string and the casing, and maintaining said connected inner pipe string in said casing with its upper end extending at least above the earth's surface and with its lower end extending downwardly to a point below the lower end of said casing.
